UNITED STATES PATENT OFFICE.

CHRISTOPHEA LEFFINGWELL, OF NEW YORK, N. Y.

WRITING-TABLET.

SPECIFICATION forming part of Letters Patent No. 532,569, dated January 15, 1895.

Application filed April 3, 1894. Serial No. 506,191. (No model.)

To all whom it may concern:

Be it known that I, CHRISTOPHEA LEFFINGWELL, a resident of New York, in the county of New York and State of New York, have 5 invented certain new and useful Improvements in Writing-Tablets; and I do hereby declare the following to be a full, clear, and exact description of the invention, such as will enable others skilled in the art to which 10 it appertains to make and use the same.

My invention relates to an improvement in writing tablets,—the object of the invention being to provide simple and efficient means whereby a continuous sheet of paper can be 15 readily moved over the tablet as it is used, and to so construct the device that the paper can be readily reversed and written upon on both sides, if desired.

A further object is to so construct a writing tablet having rolls for the reception of a continuous sheet of paper, as to render it easy 20 to remove and replace the rolls.

With these objects in view the invention consists in certain novel features of construction and combinations and arrangements of parts as hereinafter set forth and pointed out 25 in the claim.

In the accompanying drawings: Figure 1 is 30 a plan view. Figs. 2, 3, and 4 are sectional views.

A represents the body of my improved tablet, which may be made of wood or metal, and at each end is provided with ears or enlargements a, b. When the device is made of 35 metal these ears or enlargements will preferably be made integral with the body portion A.

The construction of the devices at both ends of the device for supporting the rolls being the same, a description of one set will suffice 40 for both.

The ear or enlargement a is perforated for the accommodation of a journal bearing a' having a recess a³ at its inner end for the reception of one end of a roll a³, and in order 45 to retain said journal bearing in fixed position, it is provided with collars a⁴, a⁵, adapted to lie parallel with the respective faces of said ear or enlargement a.

The ear or enlargement b is made with a 50 perforation b', in which a journal bearing c is adapted to fit loosely, the inner end of said journal bearing being made with a recess c'

for the reception of the other end of the roll a³, and projecting from said inner end of the journal bearing is a spur c² adapted to enter 55 a slot c³ in the end of the roll a³. The outer end of the journal bearing c is made with a knob d, by means of which to turn it. A catch e is pivotally connected at one end to the ear or enlargement b and at its other end, 60 is made with a recess e² adapted to receive a projection e⁴ on said ear or enlargement, whereby said catch will be retained in position. Between its ends the catch is made with a slot f of a diameter less than that of 65 the journal bearing c where the latter passes through the ear or enlargement b. The journal bearing c is made with a groove g into which the catch is adapted to enter when the device is in use, and thus prevent the accidental escape of said journal bearing. The 70 catch is also provided with a thumb piece e' by means of which to operate it.

A continuous strip of paper (either plain or ruled, as desired) will be fastened to the 75 two wooden rolls a³ before they are placed in position, and wound tightly on one of said rolls. The rolls will then be placed in position, one at each end of the device, one end of each roll entering the rigid journal bearings. The removable journal bearings c will 80 then be placed in position to receive the other ends of the rolls, the spurs c² entering the ends of said rolls. The catches will then be adjusted to prevent the escape of the removable 85 journal bearings. The tablet is then ready for use.

After using as much of the exposed paper as desired, the journal which engages the empty wooden roll will be turned, winding 90 the paper upon the same and unwinding it from the other roll. When it is desired to refer to any thing previously written, it is merely necessary to wind the paper on the roll from which it had just been unwound, thus 95 drawing the paper back until the desired point is reached.

It will be observed that the paper is wound from the top of one roll and the bottom of the other. By this means, when one side of the 100 paper has been filled, it is merely necessary to reverse the positions of the respective rolls and the other side of the paper will be exposed ready for use.

My improvements are very simple in construction, cheap to manufacture and effectual in the performance of their functions.

Having fully described my invention, what I claim as new, and desire to secure by Letters Patent, is—

The combination with the body portion of a writing tablet having ears or enlargements at the four corners, and a journal bearing 10 permanently connected with the body portion at both ends thereof, of removable bearings in the ears or enlargements opposite the fixed bearings, all of said bearings having recesses, rollers held at their ends in the re-

cesses, said removable bearings having annular grooves formed therein, and latches pivoted to the body portion in position to enter the annular grooves whereby to lock said bearings in the ears or enlargements, substantially as set forth.

In testimony whereof I have signed this specification in the presence of two subscribing witnesses.

CHRISTOPHEA LEFFINGWELL.
